Primary Examiner — Austin Murphy(74) *Attorney, Agent, or Firm* — Morgan, Lewis & Bockius LLP(57) **CLAIM**

An ornamental design for a kiosk, as shown and described.

DESCRIPTION

FIG. 1 is a perspective view of a kiosk, showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines illustrating certain elements on the kiosk are for illustrative purposes only and form no part of the claimed design.
